Inventor—
Henry Shaw,
By B. Singer, Atty.

UNITED STATES PATENT OFFICE.

HENRY SHAW, OF BIRMINGHAM, ENGLAND.

WOODWORKING MACHINE.

1,402,667.

Specification of Letters Patent. Patented Jan. 3, 1922.

Application filed November 2, 1920. Serial No. 421,322.

To all whom it may concern:

Be it known that I, HENRY SHAW, a subject of the King of Great Britain, residing at 109 Summer Lane, Birmingham, in the 5 county of Warwick, England, have invented a certain new or Improved Woodworking Machine; and I do hereby declare that the following is a full, clear, and exact description of the same.

10 This invention relates to a wood working machine and has for its object to provide a machine of simple and inexpensive construction whereby wood working operations, such as jointing, planing, moulding, 15 tenoning chamfering or sawing may be conveniently carried out.

More particularly my invention relates to that type of machine which includes a table pivotally mounted at one end, the table having 20 in a guide and also having a slot through which a rotating tool or cutter projects, the arrangement being such that the wood to be operated upon is travelled along said table in contact with the table and the guide and 25 is acted upon by the cutter during its travel. In this class of apparatus it has been proposed to provide spring members to press the wood into contact both with the table and the guide.

30 The object of the present invention is to provide an improved machine of simple construction and in accordance therewith the machine comprises a table of L or angle section having a lug formed upon the under 35 side thereof, a base member, a pivot pin carried by said base member and adapted to engage the said lug to pivotally support the table, a spindle mounted on said base and adapted to carry a wood working tool, 40 means for driving said wood working tool, an opening in the table through which the wood working tool may project, means for varying the size of said opening to accommodate different tools, and an adjustable 45 abutment adapted to control the height of the table above the tool.

Referring to the drawings:

Figure 1 is an elevation of one form of my improved machine.

50 Figure 2 is a plan view of same.

Figures 3 and 4 are sectional elevation and plan view respectively.

Figure 5 illustrates one of the spring holding rods removed.

55 Figure 6 is an elevation of a modified machine.

Figure 7 is a plan view.

Figure 8 is an end elevation.

In the construction illustrated at Figures 1-5 the table 1 consists simply of a member of L or angle section provided with a lug 2 upon its underside at one end whereby it may be pivoted. This table is provided with a slot or opening 3 at about the centre of its horizontal face through which a wood working tool may project. This opening may be adapted to receive one of a series of plates 5 each having a different sized opening to accommodate or suit different tools. These plates are secured in position in the upper part of said opening and in countersunk relation with the horizontal surface of the table by means of plates 6 which are secured to the table by screws 7 or other means and to the plates by means of the countersunk screw 8.

The holes in said table or in said plates may be of larger sectional area at the bottom than at the top so as to fit more closely to a rotating circular tool.

80 The plate is provided with a bridge piece 8^a to strengthen the plate being so formed to provide a clearance for the tool.

The vertical side of the table is also provided with a cut-away part 9 to provide a clearance for the bridge piece of the plate.

85 The table is pivoted to a base plate 10 which is adapted to be secured to a bench or the like by holding down screws, and between the upper surface of this base plate 90 and the under surface of the table at the opposite end to that where the hinge is situated is a screw device whereby the table may be swung on its pivot and adjusted and locked into any desired position. This 95 screw device may consist of a simple set screw 11 with a milled head 12 upon which rests the under side of the table. A locking nut 13 also having a milled head is placed on this screw and is adapted to be screwed 100 down on to the upper surface of the base plate.

As is usual in this class of machine, the tool is carried on a spindle 14 arranged beneath the table and I may provide bearings 105 15 for said spindle on an extension 16 of the base plate. It will be understood that the said spindle may be provided with a belt pulley as 17 in the construction illustrated or with a driving motor or other driving element. It will also be understood that 110 the end of the spindle which projects be-

neath the table is suitably shaped to accommodate any one of a number of cutters for any wood working operation which can be carried out by a rotary tool.

5 Springs of improved construction are provided whereby the wood may be kept in contact with the horizontal and vertical faces of the table. I may provide four of said springs, all of which may be of the same 10 construction. These springs also form a guard for the tool.

Each spring element may consist of a rod 19, see Figure 5, slidably mounted in a hole 20 in the horizontal or the vertical face 15 of the table, a set screw 21 being provided whereby said rod may be adjusted into any suitable position in relation to the table. One end of the rod is slotted at 22 and provided with a binding screw 23. The slot in 20 the end of the rod accommodates a steel or other plate spring 24 consisting of a long blade having one end curved so as to give the wood a lead into the spring. It will be understood that the set screw which locks 25 the spring carrying rod to the table, not only permits sliding movement of said rod but permits also a rotary movement so that the angle between the spring and the opposite face of the table can be varied as desired. I may provide two series of holes 20 on either side of the tool so that they may be disposed in the direction in which the work is being fed.

The table and the base plate may be made 35 from simple castings which are given the necessary stiffness by means of ribs or webs 26.

The table can be adjusted transversely in 40 relation to the base plate so that the gap in the table can be adjusted in relation to the position of the tool upon the driving spindle. This may be carried out by forming the base plate with two spaced bearings 28-28, in which is fixed a pivot 29. The pivoted table 45 is provided with a downwardly projecting lug 30, the thickness of which is considerably less than the distance between the spaced bearings upon the base plate. This lug is drilled so that it can be mounted upon the pivot. Passing radially into the lug is arranged a set screw 31 for locking the table to the pivot in any required position. By 50 this method of mounting the table upon the base plate the table can be moved transversely with respect to the base plate in addition to being pivoted thereto. As the table may also include a guide for the work this method of mounting the table enables the work to be positioned relative to the tool 55 with a minimum of trouble.

In the construction illustrated at Figures 6-8, instead of using gap plates, an arrangement may be provided wherein the table is provided with a gap, the size of which can

be adjusted by two adjustable plates 35-36 65 mounted upon the table. These plates are mounted in grooves 37 upon the table so that they can slide therein, locking nuts, such as set screws 38 having a wing nut 39, being provided for securing them in an 70 adjusted position. The adjacent ends 40 of these plates may be under cut to a curvature approximating to the periphery of the tools used. These plates can slide in the grooves moving either towards or away from 75 each other so as to adjust the length of the gap through which the tool works.

One of the adjustable plates 36 carried by the table may be mounted upon a number, say four, adjustable set screws 41, by which 80 the level of the plate can be adjusted, thus rendering unnecessary the accurate machining of the surface of the table which would otherwise have to be done to ensure that the table was quite square with the tool. These 85 set screws pass through holes in the table and can be screwed up or down from beneath the table. The other adjustable plate 35 carried by the table may be mounted upon members which allow the height or level of 90 the plate to be adjusted. This plate may, for instance, be mounted on a pair of spaced eccentric rollers 43, the rotation of which move the plate up or down in relation to the table. A locking screw 38 may 95 be provided carried by the adjustable plate and passing through a hole in the table and secured by a nut 39 and preferably also beneath a spring washer 42. The two eccentric rollers may be operated by cranks 44 which 100 are connected by a coupling rod 45.

The purpose of arranging the movable plates adjustable in height is so that the level of them or the level of one of them can be adjusted to compensate for the difference 105 in thickness of the material before and after it has been operated upon by the tool. If the material under treatment is caused to slide along one of the movable plates and is then operated upon by a planing tool, for 110 instance, it is clear that after passing the tool its thickness will be reduced. Consequently the movable plate which is situated beyond the tool will need to be at a slightly higher level than the movable plate which 115 supports the material before it reaches the tool.

It will be understood that although I have described a gap plate in one construction and adjustable plates in the other for varying the size of the hole in the table, any other suitable means may be provided for this purpose, either alone or in conjunction with the adjustable plates. One other way of providing a suitable gap piece to suit the 120 tool is by means of a piece of wood of a suitable size to fit within the hole in the table, the gap being subsequently cut by the wood 125

working tool itself. In this way a suitable gap piece can be easily and cheaply produced for any tool.

It will also be understood that I may also use a gap piece as illustrated in Figures 3 and 4 in the machinery having the adjustable plates for certain operations, to which the gap piece may be more suited, the table being provided with a hole to receive the plate.

What I claim then is:—

1. A wood working machine comprising a table of angle section, a base member, a pair of spaced bearings carried by said base member, a pivot pin disposed between and connecting said spaced bearings, a lug on the under side of the table which is slidably and pivotally mounted on the pivot pin to permit transverse and pivotal movement thereof, means for securing said lug in its transversely adjusted position, an adjustable abutment on said base adapted to limit the pivotal movement of said table, a spindle carried by the base, a wood working tool carried by said spindle adapted to project through an opening in the table, and means for varying the size of said opening to accommodate different tools.

2. A wood working machine comprising a table of angle section, a base member, a pair of spaced bearings carried by said base member, a pivot pin disposed between and connecting said spaced bearings, a lug on the

under side of the table which is slidably and pivotally mounted on the pivot pin to permit transverse and pivotal movement thereof, means for securing said lug in its transversely adjusted position, an adjustable abutment on said base adapted to limit the pivotal movement of said table, a spindle carried by the base, a wood working tool carried by said spindle adapted to project through an opening in the table, and a pair of adjustable plates slidably mounted on said table to vary the size of the opening in the table.

3. A wood working machine comprising a table of angle section, a lug on the under side of said table, a base member, a pivot pin carried by said base member and adapted to engage the said lug to pivotally support the table, an adjustable abutment on said base adapted to control the height of said table, a spindle mounted on said base, a wood working tool carried by said base and adapted to project through an opening in the table, a pair of adjustable plates slidably mounted on said table to vary the size of said opening to accommodate different tools, means for adjusting the heights of said plates relative to the table and to each other, and means for securing them in their adjusted position.

In witness whereof I affix my signature.

HENRY SHAW.
